UNITED STATES PATENT OFFICE

WILLIAM O. ERBES, OF EVERETT, WASHINGTON

SOUND RESONATOR

Application filed May 30, 1930. Serial No. 457,570.

This invention has reference to improvements in sound resonators of the type particularly designed to be used with loudspeakers for amplification purposes, and it presents 5 improved construction over the sound resonator for which Letters Patent of the United States, No. 1,484,119, were issued to me on February 19th, 1924.

The objects of this invention, generally 10 stated, are, to provide a sound resonator having an amplifier constructed mainly of a reinforced plastic composition which is non-resonant in character, designed to convey vibrations not only through the sound conduit 15 and main sound outlet provided but also through the solid portions thereof, thereby permitting said portions to act as a sound filtering medium; to afford, in connection with said amplifier, a plurality of sound 20 chambers each of a different amplitude and including a sounding board and a bridge, said bridge being adapted to transmit vibrations from the amplifier to the sound chamber and sounding board and being also adjust- 25 able as to tension so as to provide, in cooperation with the particular sound chamber with which it is connected, instrumentalities tuned to and adapted to make more resonant and harmonious tones of a certain register; and, 30 to make available a vent for the amplifier, which, in connection with the sound-filtering properties imparted to the amplifier by said composition, relieves the amplifier of extraneous sounds caused by electrically oper- 35 ated speaking devices, or otherwise, and permits the sound chambers and the amplifier itself to more properly perform their primary 40 functions.

Other objects, capabilities and advantages 45 will appear as the description of the invention progresses.

In the accompanying drawings—

Figure 1 is a side elevation of the entire device, the same being partly in section and 45 broken away, and having a loudspeaker installed thereon.

Fig. 2 is a cross section drawn on the line 2—2, of Fig. 1.

Fig. 3 is a horizontal section drawn on the 50 line 3—3, of Fig. 1.

Fig. 4 is a transverse sectional detail of one of a series of sound chambers connected with the amplifier of the device, including a sounding board bridge mounted in said chamber.

Fig. 5 is a side elevation of a modified form of said device.

Referring to the drawings more in detail, a base 1 is provided, having at one side a pair of spaced upstanding supports 2 and at the other side a pair of spaced upstanding and longer supports 3, said parts being, in the present embodiment of the invention, of metallic tubular construction. A crosspiece of wood, denoted as 4, is mounted on each pair of said supports, and is held against lateral displacement by sockets 5 made in the crosspieces adjacent their ends and adapted to receive the free ends of the supports. The crosspieces, designed as they are to carry an amplifier of substantial weight, will be further secured in place obviously by the weight of said amplifier.

The amplifier includes a hollow flared body portion 10, substantially rectangular in cross section, having at its front end the main outlet 11 for sounds to be conveyed therethrough and at its rear end an upstanding sound conduit 12, which communicates with the body portion. Said conduit is provided with an open and free end 13 which obviously serves as an inlet for sounds to be carried by the amplifier, and said end also affords a seat 14 for a loudspeaker, or the like. 15 denotes a sound vent located in the top of the body portion and adjacent to said conduit, and 16 a wall disposed between said vent and conduit to prevent sounds as they are introduced into the conduit from being projected into the vent.

The portions of the amplifier just described are constructed of reinforced plastic composition having nonresonant characteristics. In constructing said portions, a form is provided which is outlined to simulate said portions, the sections of said form utilized in making said conduit, vent and wall, being detachably connected with the section of the form used in making the body portion, to facilitate the removal of 100

said portions from the form. Wire meshing, denoted as 20 and having preferably nine meshes to the square inch, is first cut out in the pattern of said portions and is then applied to the form and tied in place with wire. A narrow iron band 21, secured by suitable wire fastenings to said meshing, serves as an additional reenforcing element for the end 11, as indicated in Fig. 1. 22 designates a 10 pair of spaced and projecting hardwood blocks disposed in the lower section of the body portion transversely and centrally thereof, the forward block being provided with three spaced sockets and the rear block 15 with a pair of spaced sockets, each denoted as 23, and 24 a pair of hardwood ribs each located at a side edge of said section, said blocks and ribs being stapled to the meshing. Said portions are now in condition to receive 20 the scratch coat of said composition.

The plastic composition out of which I prefer to make the scratch coat of said portions of the amplifier consists of a mixture of fine sand, crushed and rolled natural rock, 25 asbestos fiber, wood flour, magnesite, and magnesium chloride, diluted.

In preparing the composition, I use the ingredients in about the following proportions, viz., fifty-five pounds of fine sand, fifteen pounds of said rock, fifteen pounds of asbestos fiber, fifteen pounds of wood flour, forty-five pounds of magnesite and six gallons of a 22 degree Baumé solution of the magnesium chloride, the said ingredients being 30 thoroughly blended.

The composition when thus prepared is applied with a trowel and a thickness as desired and which will serve to hold the parts in place when said coat has been dried sufficiently to permit handling, the same requiring 40 from twelve to twenty-four hours under usual drying conditions. Said coat having been dried the form is removed, and the amplifier as now constructed is in condition 45 to receive the frames of three sound chambers which are formed integral with said body portion. While said frames vary in size one from the other, each is otherwise identical in construction and performs a like function, 50 consequently each is given the same numerical designation, 25.

In forming one of said frames, a strip of said wire meshing of suitable width and length is cut, and a narrow section of one 55 edge is bent in right angular relation with the body of the strip so as to form a flange by which the strip may be secured conveniently in an upright position to the body portion of the amplifier. Said strip having been bent 60 into a form having a frusto-conical outline and of a size appropriate for the sound chamber of which it is a part, suitable holes are then punched through the scratch coat of the amplifier so as to expose the meshing and the 65 strip is placed in proper position and wired

to said meshing. A mold is then placed over said strip, and it is now ready to receive the plastic composition of which the frame is mainly formed.

The plastic composition out of which I 70 prefer to make said frames and to provide a finish coat for said portions of the amplifier consists of a mixture of fine said, crushed and rolled natural rock, asbestos fiber, wood flour, magnesite, and magnesium chloride, diluted. 75

In preparing the composition, I use the ingredients in about the following proportions, viz., twenty-five pounds of fine sand, twenty-five pounds of said rock, twenty-five pounds of asbestos fiber, twenty-five pounds of wood 80 flour, forty-five pounds of magnesite and six gallons of a 22 degree Baumé solution of the magnesium chloride, the said ingredients being thoroughly blended.

This composition is then placed in the mold 85 to form said frame, strips of wood 26 being inserted in the mold and embedded in the composition in spaced relation with the outer edges of the frame, so as to afford means by which a top member may be fastened to the frame, as will be presently and more particularly described. Each of said three frames is applied to the amplifier in a like manner. When said frames have become sufficiently 90 dried to permit handling, the molds are removed and the amplifier is in condition to receive the finish coat.

Said finish coat is applied with a trowel 100 interiorly and exteriorly of said portions, and is smoothed down in a way to give said portions and the connections of said frames with the body portion a neat and finished appearance. As is evident, the thickness of the combined scratch and finish coats will vary with the size of the amplifier, but I have found in 105 actual practice with this composition a maximum thickness of from three-fourths inch to one and one-fourth inches will provide structures which are substantial and satisfactory. Under ordinary drying conditions about 110 fourteen days are required for said structure to become thoroughly air cured, when it may be then painted or otherwise decorated to suit.

The amplifier, having been seated on the 115 crosspieces 4 with the ribs 24 contacting therewith, as indicated in Fig. 1, is now in position to receive an assembly of parts disposed between it and the base. Said assembly comprises a sound chamber which is designated 120 30 as an entirety, the same being frusto-conical in outline and having its bottom, side and end portions constructed of maple and generally designated as 31, the top of said chamber, which functions as a sounding board 125 32, being preferably of vertically grained spruce secured in place by wooden dowels. 33 denotes a reenforcing strip of maple secured to the inner periphery of the top and extending longitudinally and centrally 130

thereof, and to which is secured a transversely extending maple block 34, said strip and block being fastened in place by wooden dowels. Further included in said assembly are 5 two sounding board bridges of like construction, one, designated as 35, being disposed interiorly of the chamber and secured by wooden dowels to the block 34, and the other, denoted as 36, being disposed exteriorly of 10 the chamber and spaced away from the top thereof, the same being secured to the sounding board bridge 35 by a pair of maple posts 37 secured adjacent each end of said bridges and which posts extend through and 15 are spaced away from the sounding board 32 so as to permit movement of said posts relative to said board and also to provide sound openings 38 in the sounding board. Said sounding board bridges are made preferably of from three to five ply maple veneer, 20 as the size of the instrument may require, and each is in the form of a figure 8, as indicated in Fig. 3, its form being designed to prevent an air lock and to permit the bridge 25 to freely perform its functions as the same will subsequently appear.

Said assembly so far described is connected with the amplifier by a plurality of posts 39 of maple secured adjacent each end of the sounding board bridge 36, said posts being also secured in the blocks 22 projecting from the amplifier and provided with the sockets 23 adapted to receive the posts. As more 30 clearly appears in Fig. 3, the assembly last referred to is thus connected with the amplifier forwardly by three of the posts 39 and rearwardly by a pair of said posts, and, as 35 shown in Fig. 2, the sound chamber is suspended above and clear of the base.

A pair of spaced cleats 40 are secured on each side of said sound chamber and extend longitudinally thereof, the same providing supports for a bolt 41 disposed adjacent each corner of said chamber and also connected 40 with the crosspieces 4 by the winged nut and washer, generally denoted as 42. Said bolts and nuts afford means for raising or lowering the sound chamber and thereby adjusting the tension of said sounding board bridges, as 45 will be described with more particularity hereinafter, and they also obviously serve to support said chamber.

The three sound chambers, the frames of 50 which are integral with the body of the amplifier and have been described, are of like construction and each carries like parts, the same differing only in size, hence the parts thereof are given like numbers. The smaller 55 of said chambers and the parts which cooperate therewith are denoted generally as 50, the same of medium size as 51, and the same of larger size as 52. Each chamber is provided with a top of vertically grained spruce 60 which functions as a sounding board 53 and having a plurality of "f" sound openings 54,

said board being secured to the frame 25 by inserting wooden dowels through it and the wood strips 26 disposed in the frame. Each sounding board denoted as 53 is essentially 65 of the same construction as the sounding board 32, differing therefrom only in size and in certain apertures provided for sound openings. Each of said three sound chambers is also equipped with certain parts of the 70 same construction as like parts provided for the sound chamber 30, and are given the same numerical designations, the sizes of the same, however, being such as to accommodate them to the particular sound chamber in 75 which they are to be installed. The block 34, secured by wooden dowels to the sounding board 53, supports a sounding board bridge 35, the same being apertured to take the bolts 41, and adjustable as to tension by said bolts and winged nuts and washers 42, a set of 80 which is disposed adjacent each end of said bridge. As is shown particularly in Fig. 4 said bolts extend through the body portion 85 of the amplifier and are operable for adjustment 80 interiorly of said portion.

In operating the device, a loudspeaker 60, for instance, communicating with a source of sound, is placed on the seat 14 so as to convey the sound vibrations transmitted through said loudspeaker to the sound conduit 13, as indicated in Fig. 1. Each of the four sound chambers heretofore described is designed to have an amplitude which will make it particularly responsive to tones of a certain register, the sound chamber 30 accommodating 90 the bass sounds, and the sound chambers 50, 51 and 52 taking care of the tenor, alto and baritone sounds respectively. In putting the bridges associated with said chambers in condition so that they will best perform their 95 functions, adequate tension is imparted to them by tightening the bolts 41 so as to tune them to the tones of the register for which each is particularly adapted, less tension being applied to accommodate the low tones 100 than is required for the higher tones. For instance, while the two bridges associated with the chamber 30 for bass sounds would be secured under positive tension, the bridge 105 enclosed by the chamber 50 for tenor sounds would be tensioned to a considerably greater extent, the exact degree of tension to be imparted to each being determined by the ear 110 of the user as the sounds from the loudspeaker are transmitted through the device, as is usual in tightening the head of a drum or in tuning stringed musical instruments.

Said sound chambers, including the sounding board and bridges associated therewith, 115 each function in a way similar to the body member and bridge of a musical instrument of the violin type, through air motion therein; each chamber and said parts being proportioned and adapted to make more resonant and harmonious the particular sounds it is 120 125 130

sensitive to and designed particularly to act upon. For instance, the chamber 30 and said parts are the largest in size and two bridges are associated with this chamber so that the same will more effectively act upon the low or bass sounds, which sounds obviously have the greatest volume. The other three chambers, each of which requires less amplitude to perform its part in the device, together with 10 certain of their parts as described, are progressively decreased in size to adapt each to the volume of sound that it is sensitive to and likewise designed to act upon. As said sound vibrations are projected through the amplifier, the same, ranging from the bass to the tenor as here designated, are taken up by the respective sound chamber assemblies and the tones thus acted upon are increased in resonance, are rounded out and rendered 20 more harmonious.

The body portion of the amplifier, by virtue of its stonelike qualities and density, will permit sound vibrations to pass through it with greater velocity than would be permitted 25 by said sound chambers, consequently imperfections in the reproduction of sounds mechanically and other extraneous sounds for which said chambers are not particularly sensitive will be filtered through the body of the 30 amplifier. It will thus be seen that the device is equipped with resonance instrumentalities acting upon the sounds which it is desired to amplify and with a filtering medium for eliminating undesirable sounds. 35 The vent 15 performs useful functions in the transmission of sound vibrations through the device in that it serves to reduce air pressure in the amplifier and permits an unrestricted circulation of air therethrough; and, it also 40 reduces the velocity of vibration so that the sounds may be amplified more slowly and evenly throughout the spaces in which the same are being acted upon.

In the embodiment of the invention shown 45 and described, the sound chambers, including the sounding board and bridges associated therewith, are designed to be of a register similar to the violin, viola, violoncello and bass-viol respectively, of the usual proportions, however, certain of said chambers and 50 said parts may be varied so as to register with the violin, viola and violoncello of smaller sizes.

While the device shown in Fig. 1 is completely operative as a unit and may be made in any suitable size, it is obvious that greater sound-volume may be had by assembling a plurality of said units, and each of which may be varied in size, as desired. Such an assembly is particularly effective where the device is utilized in large theaters, or the like, in amplifying sounds from phonographic records, radio, or in other ways.

The modified form of the invention shown 65 in Fig. 5, is constructed in identically the

same manner as described relative to the preferred form of the invention, except that the sound chambers 50, 51 and 52 and the tensioning elements associated therewith are eliminated, and the amplifier presents the 70 same construction as heretofore described, consisting mainly of a reenforced plastic composition structure. The parts shown in the modified form are given the same numerical designations as heretofore given for the 75 like parts in the preferred form.

The single sound chamber of this device may have an amplitude which is suitable and adapted to register with tones of the quality that the instrument is particularly designed 80 to act upon, said chamber performing its functions in the manner heretofore described. The amplifier, in addition to its ordinary function, will also serve as a filtering medium and said vent will cooperate with the amplifier and said chamber in transmitting sounds through the device, as has been detailed. This form may also be utilized in series, in which event each unit preferably 85 would be adapted to act on tones of a certain 90 register and consequently would be of a different size, the entire assembly serving, like the first-named assembly, to enrich and make more sonorous the sounds transmitted thereby, and also to enhance the volume of sound. 95

I have found in actual practice that excellent results may also be obtained through an assembly consisting of the device as shown in Fig. 1, and three units of the modified form 100 designed to be of a register similar to the violin, viola and violoncello respectively.

Changes in and modifications of the construction described, other than those referred to herein, may be made without departing from the spirit of my invention or sacrificing 105 its advantages, hence it is desired that I be not confined to the specific structures set forth, except as limited by the appended claims.

I claim:

1. A sound resonator, comprising a base, an amplifier supported in elevated position above the base, a sound chamber disposed between the lower periphery of the amplifier and the base, said chamber defining in its upper portion an apertured sounding board, a bridge located within said chamber and adapted to communicate sound vibrations from the amplifier to the sounding board, adjustable means for imparting tension to said bridge, said chamber, sounding board and bridge being of a certain amplitude, and a plurality of sound chambers connected with the body of the amplifier, each defining in its upper portion an apertured sounding board and having a bridge located interiorly of the chamber adapted to communicate sound vibrations from the amplifier to the sounding board, and adjustable means for imparting tension to the last-named bridges, each 110 115 120 125 130

of the last-named chambers, including their sounding boards and bridges, being of an amplitude different from the first-named chamber, sounding board and bridge and of an amplitude different one from the other.

5 2. A sound resonator, comprising a base, an amplifier supported in elevated position above the base, said amplifier having a hollow flared body portion constructed of nonresonant reenforced plastic material and provided with a sound inlet and a sound outlet, a vent for the amplifier, a sound chamber disposed between the lower periphery of the amplifier and said base, said chamber defining in its upper portion an apertured sounding board, a bridge enclosed within said chamber and operatively secured to the sounding board, a second bridge located exteriorly of said chamber and above the sounding board, 15 a plurality of sound posts extending through the sounding board and connecting said bridges, a plurality of sound posts connecting the second bridge with the amplifier, and means for raising or lowering said chamber to impart tension to said bridges.

25 3. A sound resonator, comprising an amplifying horn made of nonresonant reenforced plastic material, a plurality of sound chambers each operatively connected with the horn and having an upper portion defining a sounding board, a bridge adapted to communicate sound vibrations from the horn to the sounding board, and means for adjustably imparting tension to the bridge, 30 each of said sound chambers being of a different amplitude.

4. In a sound resonator, an amplifier, and a plurality of sound chambers each having a sounding board and a sounding board bridge, said bridge being adapted to communicate sound vibrations from the amplifier to the sounding board, each of said sound chambers and the sounding board and bridge directly associated therewith being particularly adapted to register with tones of a different quality.

45 5. In a sound resonator having an amplifier, a sound chamber assembly, comprising a sound chamber defining in its upper portion a sounding board apertured to receive sound posts and to provide sound openings, an apertured bridge located within said chamber and operatively secured to the inner periphery of the sounding board, a second bridge of like construction disposed exteriorly of said chamber and above the first-named bridge, a plurality of sound posts extending through the sounding board and connecting said bridges, a plurality of sound posts connecting the second-named bridge with the amplifier and adapted to communicate sound vibrations from the amplifier to said bridges, and means whereby tension may be adjustably imparted to said bridges.

65 6. In a sound resonator having an am-

plifier, sound chamber operatively connected with the amplifier and defining in its upper portion an apertured sounding board, an apertured sounding board bridge located within said chamber and secured to the inner periphery of the sounding board, and adjustable means for imparting tension to said bridge.

70 7. In a sound resonator having an amplifier and a sound chamber associated with the amplifier, a sounding board operatively connected with said chamber, a bridge secured to said sounding board and adapted to transmit sound vibrations from the amplifier to the sounding board, and means for applying tension to said bridge.

75 8. In a device of the class described, an amplifying horn constructed of a nonresonant reenforced plastic composition, said horn having a hollow flared body portion provided at one end with a sound outlet and at the other end with a sound conduit communicating with said portion and having a sound inlet, a seat at the free end of said conduit for a mechanical sound reproducer, and 80 a sound vent located adjacent said seat.

90 9. In a sound resonator, the combination of an amplifying horn constructed of nonresonant reenforced plastic material adapted to filter out extraneous sounds, and a plurality of sound chambers associated with said horn each being sensitive to and active upon tones of a different register.

95 10. In a device of the class described, an amplifying horn having a body portion constructed of nonresonant artificial stone cementitious in character and of a density adapting it to act as a sound-filtering medium, and metallic reenforcing elements embedded in said material.
